UNITED STATES PATENT OFFICE.

JOHN J. LISBAE, OF CANTON, OHIO, ASSIGNOR TO THE SANITARY RUBBER COMPANY,
OF CANTON, OHIO, A CORPORATION OF OHIO.

SOAP-HOLDER.

1,088,783.

Specification of Letters Patent.

Patented Mar. 3, 1914.

Application filed September 15, 1911, Serial No. 649,574. Renewed January 22, 1914. Serial No. 813,774.

To all whom it may concern:

Be it known that I, JOHN J. LISBAE, a citizen of the United States, residing at Canton, in the county of Stark and State 5 of Ohio, have invented a new and useful Soap-Holder, of which the following is a specification.

My invention relates to improvements in devices for holding cakes of soap in such 10 manner as to permit water to drain freely therefrom after the same have been used and placed in the holder, and to a peculiar construction of such holder wherein the water drained from the soap is conducted in 15 definite channels through and out of the holder, thus preventing the accumulation of drainage in the holder itself.

The objects of the invention are to generally improve devices of the character 20 mentioned, to provide a soap holder more efficient in draining the soap placed therein and directing the discharge of the drainage therefrom, to make the device of flexible water-proof material, such as rubber, to 25 construct the device in sections or parts adapted to be connected together to form a holder of any desired capacity, and in general to provide a satisfactory and sanitary soap holder of practical utility. These objects, together with other objects readily apparent to those skilled in the art, may be attained by the construction illustrated in 30 the accompanying drawings, although the invention may be embodied in other forms, 35 the construction illustrated being chosen by way of example.

In the drawings Figure 1 is a perspective view of a top section of a soap holder embodying the invention. Fig. 2 is a perspective view of an intermediate section. Fig. 40 3 is a perspective view of a bottom section. Fig. 4 is a front view partly in elevation and partly in vertical section of a soap holder formed of a number of such sections 45 as are shown in Figs. 1, 2 and 3. Fig. 5 is a vertical sectional view taken on the line 5-5 of Fig. 4. Fig. 6 is a top view of one of the intermediate sections.

Throughout the several views similar reference numerals indicate similar parts.

The holder preferably comprises top, intermediate and bottom sections, said sections being made of rubber or similar material and connected together as by vulcan-

izing or the like so as to form a substantial 55 integral structure. The upper section is provided with the back 1 preferably having near the top a hanging aperture 2 provided with reinforced edges, as shown in the drawings. The lower portion of the 60 back 1 is rabbeted on the rear side at 3 for substantially half the thickness of the back for the purpose hereinafter to appear. Formed integrally with the back 1 is a soap 65 holding tray having the bottom 4, front 5 and sides 6, the sides preferably curving upwardly and, rearwardly to more thoroughly brace and sustain the tray in its proper horizontal position with reference to the normally vertical back. The upper 70 surface of the bottom 4 is so disposed as to have a pitch or fall sufficient to drain water backwardly and the said bottom is provided with the integral raised ribs 7 adapted to support a cake of soap in spaced relation with 75 reference to the upper surface of said bottom. At the rear of the bottom 4 a depressed transverse channel 8 is provided into which channel drainage from the bottom 4 may discharge whence it may flow laterally in 80 said channel to the drainage apertures 9. Formed integrally with the top section the short drainage tubes 10 lead downwardly from the apertures 9 and terminate in a 85 horizontal plane in line with the lowermost edge of the section, the lower ends being reduced in diameter at 10^a as shown. Each intermediate section is provided with a back 1^a the upper portion of which, on the front side is rabbeted at 11 for substantially 90 half the thickness of said back, the recess thus formed being adapted to receive the corresponding projection of the upper section formed by the recess at 3 so as to form a matched rabbet-joint as is clearly 95 shown in Fig. 5. At the lower portion of the back 1^a the said back is rabbeted on the rear side at 12 forming a similar recess to that at 3 in the upper section.

Formed integrally with the back 1^a is a 100 soap holding tray formed substantially the same as the tray of the upper section and provided with similar bottom 4^a, front 5^a, sides 6^a, ribs 7^a, channel 8^a and discharge apertures 9^a. Formed integrally with the 105 intermediate section the short drainage tubes 10^a lead downwardly from the apertures 9^a and terminate in a horizontal plane

in line with the lowermost edge of the section, in similar manner to the tubes 10 of the top section, their lower ends being similarly reduced at 10°.

5 Located in the inner vertical corners between the back 1^a and sides 6^a and formed integrally with said back and sides the relatively long drainage tubes 13 extend from the line where the back 1^a is cut away at 11 downwardly to a point slightly above the channel 8 where they terminate immediately above the apertures 9^a into which apertures drainage passing downwardly through said tubes 13 will be discharged. It will be 15 noted that the tubes 13 at their tops are internally enlarged at 13^y to receive the reduced ends of the tubes 10. In connecting the upper section with an intermediate section the tubes 10 are arranged immediately 20 over the tubes 13 and connected thereto so that said tubes 10 may discharge into the tubes 13.

Each bottom section is provided with a back 1^b having a projection 14 adapted to 25 fit the recess at 12 of an intermediate section so as to form a rabbet-joint such as hereinbefore described. Formed integrally with the back 1^b is a front piece 15 connected to the back 1^b only along the outer edges 16, 30 which edges converge as they extend downwardly, being preferably curved as shown in the drawings. The front piece 15 adjacent said edges is provided with outwardly spaced walls 17 forming, with said back, 35 drainage tubes 18 adapted to receive drainage from the short drainage tubes 10^a of the intermediate section. The drainage tubes 18, at their lower ends converge and unite in the median line of the holder forming a 40 common discharge outlet 19. Intermediate the outwardly spaced walls 17 the front piece 15 normally lies adjacent the back 1^b as shown in full lines in Fig. 3. When it is desired to cleanse the holder, however, and 45 remove any accumulation in the tubes 18 the front piece may be drawn away from the back as shown in dotted lines in Fig. 5.

It will be readily apparent that in assembling the sections to form a soap holder any 50 desired number of intermediate sections may be employed together with a top and bottom section. In Figs. 4 and 5, however, a holder is illustrated in which two intermediate sections are used with a top and bottom 55 section, thus providing three trays. All joints between the various sections and tubes should be thoroughly vulcanized or otherwise treated to produce a firm union between the complementary projections, thus producing a unitary structure. The drainage 60 from soap placed in the various trays, being carried down the slanted surfaces of the bottoms finds its way into the transverse channels at the rear of the trays and thence 65 through the drainage apertures and drain-

age tubes downwardly into the converging drainage tubes 18 whence it is carried out through the discharge outlet 19.

In the normal use of the device, where the same is suspended over a sink, laundry tray 70 or the like the drainage discharge from the outlet 19 may be permitted to fall into said sink or tray. Should it be desired, however, to suspend the holder at a point where it is not practical to permit the drainage to be 75 thus openly discharged from said outlet a tube may be connected to said outlet, if desired, and the drainage further directed in its course.

By forming the soap holder of rubber or 80 similar, soft, flexible material provision is made for compressing the article, if necessary, for shipment, the holder being adapted to be packed tightly with other holders without injury. In this connection it should be 85 noted that the device is also non-breakable.

In cases where much washing is done soap 90 holders of my invented construction will be especially appreciated, as long continued use of soap and water greatly softens the skin of the hands, and in hurried work, in re-placing the soap in the holder, or taking the soap from the holder a quick movement of the hand and firm grasp of the soap will in no wise endanger the person in striking 95 the hand against the holder and thus injuring the already softened hands. Should the holder fall from its hook or support into an enameled sink or the like no injury will be done to either sink or holder as in the case 100 with constructions now commonly in use. Again, the rubber construction provides an absolutely non-corrosive holder which may be easily and thoroughly washed and cleaned, the flexible character of the device enabling 105 the thorough cleaning of all tubes and other portions. By conducting the drainage from the soap in the tubes the drainage is immediately removed from the holder without filling a visible receptacle, while making it 110 possible to direct said drainage wherever desired. These points of advantage become of more importance with the increase of use of a soap holder.

While my invented holder is serviceable 115 and desirable in cases where the soap is seldom used, its advantages are much more apparent in cases where washing and cleaning and the consequent use of soap is practically continuous.

I claim:

1. A soap holder made of pliable material and comprising a back, a plurality of soap holding trays formed integrally with said back and arranged one above another, each 120 tray having a bottom, front and sides, said bottom having a declination from said front to said back and provided with integral raised ribs in front-to-rear position, a depressed transverse channel in said bottom 130

adjacent said back, drainage tubes formed integrally with said back and extending from the rear inner corners of the uppermost tray downwardly through the rear inner corners of the lower trays, said tubes in each of said lower trays being cut away to form drainage apertures leading from said transverse channels into said tubes, said tubes terminating below the lowermost tray,
10 whereby the drainage from all of the trays on said back will be carried downwardly through said tubes and discharged therefrom below the lowermost tray.

2. In a sectional soap holder a bottom section provided with a back, a front piece formed integrally with said back and connected to said back along the outer edges of the same, said front piece provided adjacent

said edges with outwardly spaced walls forming, with said back, drainage tubes, 20 said tubes converging at their lower ends and uniting in a common discharge outlet in the median line of the section, said front piece intermediate said outwardly spaced walls normally lying adjacent the back and 25 adapted to be drawn away from said back to permit access to the interior of said drainage tubes.

In testimony that I claim the above, I have hereunto subscribed my name in the 30 presence of two witnesses.

JOHN J. LISBAE.
